Primary Examiner — Sanjeev Paul*Assistant Examiner* — Rene H. Kadoo(74) *Attorney, Agent, or Firm* — Kelly McGlashen; Maginot, Moore & Beck LLP(57) **CLAIM**

The ornamental design for a rotary cutting tool as shown and described.

DESCRIPTION

FIG. 1 is a perspective view of a rotary cutting tool showing our new design;

FIG. 2 is a top plan view thereof;

FIG. 3 is a bottom plan view thereof;

FIG. 4 is a right side elevational view thereof; and

FIG. 5 is a left side elevational view thereof.

FIG. 6 is a front elevational view thereof; and,

FIG. 7 is a rear elevational view thereof.

In the drawings, broken lines represent the environment of the claimed design and form no part of the claimed design.

1 Claim, 4 Drawing Sheets(56)
